DESIGN FOR A HOLDER FOR PAPER CUPS

Lawrence M. Turner, North Abington, Mass.

Application October 5, 1946, Serial No. 133,783

Term of patent 14 years

(Cl. D44—24)

To all whom it may concern:

Be it known that I, Lawrence M. Turner, a citizen of the United States, residing at North Abington, county of Plymouth, and Commonwealth of Massachusetts, have invented, a new, original, and ornamental Design for a Holder for Paper Cups, of which the following is a specification, reference being had to the accompanying drawings, forming a part thereof.

Fig. 1 is a plan view of a paper cup holder showing my new design; and Fig. 2 is an elevational view thereof.

I claim:

The ornamental design for a holder for paper cups, substantially as shown.

LAWRENCE M. TURNER.
